JASPER C. OWENS, OF BRIDGEPORT, CONNECTICUT, ASSIGNOR OF ONE-HALF TO SILAS T. VELIE, OF BRIDGEPORT, CONNECTICUT.

CARPET-STRETCHER.

1,160,647.

Specification of Letters Patent. Patented Nov. 16, 1915.

Application filed November 8, 1913. Serial No. 799,922.

To all whom it may concern:

Be it known that I, JASPER C. OWENS, citizen of the United States, residing at Bridgeport, in the county of Fairfield and State of Connecticut, have invented certain new and useful Improvements in Carpet-Stretchers; and I do hereby declare the following to be a full, clear, and exact description of the invention, such as will enable others skilled in the art to which it appertains to make and use the same.

My invention relates to carpet stretchers and is particularly adapted for laying carpets and linoleum over concrete floors.

Referring to the drawings wherein the same figures and letters of reference indicate like parts throughout the several views: Figure 1 represents a side elevation of the carpet stretcher; Fig. 2 is a cross sectional view of the handle lever on line *a a*, and the body portion on line *b b* of Fig. 1, showing the operating lever turned to one side; Fig. 3 is a broken view partly in section of the carpet stretcher in operation on a carpet laid on a concrete floor; Fig. 4 is a broken view of the stretcher equipped for laying linoleum; Fig. 5 is a broken view of a modified construction adapted for use in laying heavy carpet and linoleum in connection with the ratchet feature of the device; Fig. 6 is an upper plan view of the device shown in Fig. 5; and Fig. 7 represents a floor plan showing a carpet partially stretched and held by stay tacks.

The device shown in Figs. 1, 2 and 3 consists of the tubular body 1 adapted to receive the longitudinally movable rack 2 held against forward movement by the pawl 3 pivotally located between the ears *3^a* of the body 1, and is kept in contact with the rack by means of the spring 4. 5 is a link pivotally supported at one end to the screw 6 of the rack and the pin 7 of the stud 8 carried by the handle lever 9 having the spear point 10 in its forward end. The foot 11 is provided with the retaining points 12 and it has the round, hollow shank 11^a inserted within the body 1 and embracing the round rack 2 as shown more clearly in Fig. 2. This shank and foot 11 are integral with the arm 11^b, and said shank is retained in place by the spring retaining screw 4^a. The opposite end of the body 1 carries the angle piece 13 having the pressure plate portion 14 adapted to rest on the floor and carrying

the retaining point or spur 15 adapted for use only on wooden floors. 16 is a metal cup secured to the rear end of the body 1, and 17 is a pad or buffer secured to said cup, the purpose of which will be presently explained. In laying a carpet the barbed foot 11 is located back from the edge of the carpet 18, Fig. 3, and the operator's knee will strike the pad 17 with force sufficient to stretch the carpet toward the base board 19. In doing this, the operator's knee will not forcibly rest on the plate 14 until after the carpet has been kicked forward as far as can be done by the operator's knee, then the operator's weight is applied to plate 14 to hold the device in its advanced position. The handle lever is then thrown forward with its spear point 10 anchored in the floor, and when thus located the pressure on plate 14 is then released and the lever 9 actuated back and forth to further advance the carpet, with the operator's knee against the pad, following up this advance so as to prevent the device retreating, and hold it in its advanced position while the spear point is released and the handle lever thrown to one side, Fig. 2, with the rack 2 out of engagement with its pawl so as to give a clear overhead space for the operator to drive the stay tacks *c*, Fig. 7, in the corners and at intervals around the edge of the carpet. The intermediate spaces *d*, between the stay tacks, are stretched by kicking the pad 17 as before mentioned. If desired, the operation above described may be reversed by first stretching the carpet as much as possible by means of repeated blows against the pad and then applying the handle lever 9. When the handle lever 9 is moved forward to advance the foot 11, the rack is held stationary by the pawl 3, and when the lever is reversed to get a fresh purchase, the rack is also retreated a notch or two, as the case may require, to give additional leverage for the handle lever to further stretch the carpet.

For laying linoleum, the lever 20, Fig. 4, is pivotally supported on the screw 6 and the link 5, which, in the previously described constructions, is also pivoted on this screw, is now pivoted on the screw 21 located in the extension 22 of the lever 20. To prevent the retaining points of the foot 11 entering the linoleum, the shoe 23 is temporarily placed over the retaining points and the edge of the linoleum. 24 is brought around the shoe and

over the top of the foot 11 and is held there temporarily by the lever 20 while the stretcher is operating. In laying linoleum the rack is always held stationary and the spur 15 in plate 14 is removed.

The construction shown in Figs. 5 and 6 is particularly adapted for laying very heavy carpet and linoleum. The same barbed foot 11, rack 2, body 1, angle 13 and 10 its plate 14 and link 5 are used as in the other construction. In this construction for heavy work, the operating lever 25 is pivotally supported on the screw 26 of the projection 26^a integral with the body 1. The 15 lower end of this lever carries the rack actuating pawl 27, and 28 is a rack retaining pawl pivotally supported on screw 29. 30 is an anchor plate pivotally connected to the outer end of the link 5 and carries the retaining points 31.

In operating this device, the anchor plate is placed against the base board of the room and held there by one foot of the operator resting thereon with sufficient pressure to 25 cause its retaining points to hold while the operator's other foot will rest on the plate 14, at the opposite end of the stretcher, with just force enough to keep said plate on the carpet, then the handle lever 25 is actuated 30 back and forth to advance the device and carry the carpet with it toward the base board in position for tacking.

In using this construction for linoleum, the points 12 are protected by the shoe 23, 35 Fig. 4, or by any other well known means, and the edge of the linoleum is held between the serrated faces of the clamp 32 and the leg 11^b above the foot 11. 33 are the clamping screws for said clamp.

40 The retaining point or points 15 are not absolutely essential, in fact, can be dispensed with altogether, as they would not be used for heavy work or on concrete floors, such as the concrete floor 34, Fig. 3. In concrete 45 flooring, the narrow wooden strip 35 forms a border around the room to which the carpet is fastened.

Copies of this patent may be obtained for five cents each, by addressing the "Commissioner of Patents, Washington, D. C."

Having thus described my invention, what I claim is:—

1. A carpet stretcher comprising a tubular body, a rack longitudinally movable therein, a barbed foot carried by the body adapted to grip the carpet, a spear pointed handle lever, a link pivotally connected to the lever and rack, a pawl to engage the rack and hold the same stationary when the handle lever is actuated to stretch the carpet and to retreat to a new fixed position when the handle lever is thrown back.

2. A carpet stretcher comprising a tubular body, a rack longitudinally and rotatably movable therein, a spear pointed handle lever, a link pivotally connected to the lever and rack, a pawl to engage the rack and hold the same stationary when the handle lever is actuated to stretch the carpet, and to retreat to a new fixed position when the handle lever is thrown back, a barbed foot having a hollow shank adapted to be inserted in the forward end of the tubular body and embracing the rack, said rack adapted to rotate to throw the handle lever to one side to give a clear open space for driving tacks.

3. A carpet stretcher comprising a tubular body, a rack longitudinally movable therein, a spear pointed handle lever, a link pivotally connected to the lever and rack, a pawl to engage the rack and hold the same stationary when the handle lever is actuated to stretch the carpet, and to retreat to a new and fixed position when the handle lever is thrown back, a barbed foot connected to the forward end of the rack, a pressure plate connected to the rear end of the rack, and a cup carrying a buffer pad connected to the rear end of the rack and located above the pressure plate.

In testimony whereof I affix my signature in presence of two witnesses.

JASPER C. OWENS.
